United States Patent

Des. 242,012
Patented Oct. 26, 1976

242,012

ICEDRILL

Reino Kotajarvi, 99600 Sodankyla 3, Finland

Filed July 31, 1975, Ser. No. 600,792

Term of patent 14 years

Int. Cl. D8—01

U.S. Cl. D8—8

FIG. 4

FIG. 3

FIG. 2

FIG. 1

FIG. 1 is a side view of the icedrill of my new design;
FIG. 2 is another side view thereof, the drill being turned 90°;

FIG. 3 is a bottom view thereof; and

FIG. 4 is a top view of the conical tip of the drill.

The broken line disclosure of a drill brace is for illustrative purposes only.

I claim:

The ornamental design for an icedrill, as shown and described.
